COCKING MECHANISM

William Summerbell, Washington, D. C.; Edith May Summerbell executrix of said William Summerbell, deceased

Application September 21, 1944, Serial No. 555,157

2 Claims. (Cl. 89—24)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to a cocking mechanism for guns of the semi-automatic type having a vertically sliding breechblock, and is an improvement upon the cocking mechanism described in my Patent No. 2,279,352, granted April 14, 1942.

The particular improvement contemplated comprises adding manually operated means to the structure of the cocking mechanism of the patent whereby the firing mechanism may be cocked from the side of the gun in case of misfire. These means include a cam member pivotally mounted on the breech ring of the gun, adapted to rock the camming lever by means of an attached handle. In the mechanism described in the aforementioned patent, the gun could be manually cocked after a misfire only by pushing on the nose of the cocking lever from the rear of the gun to rotate the lever on its pivot. This was not only a difficult task, but an extremely dangerous one due to the possibility of premature firing of the live projectile in the gun. This new cam member serves a double purpose in also providing a camming surface for the cocking lever in normal cocking of the gun during recoil and counter recoil, permitting elimination of the plunger member shown in Figure 8 of the patent.

A principal object of my invention is to provide manually operable means for cocking a gun having a vertically sliding breechblock from the side of the gun.

An important object of my invention is to provide means on the breech ring of a gun having an opening in which the breechblock is mounted to slide vertically which cooperates with the cocking mechanism enclosed in said breechblock to manually cock said gun after misfire from the side of the gun.

A further object of my invention is to provide simplified means on the breech ring of a gun having a breechblock slidably mounted therein to urge the cocking lever of said gun upward during the closing of the breech.

Another object of my invention is to provide in a gun having a breechblock enclosing a firing mechanism and a breech ring having an opening in which said breech ring is slidably mounted, a cocking mechanism which is automatically operated by the vertical movement of said breechblock in opening and closing the breech of said gun but which can be operated manually from

2

the side of the gun outside the breechblock in case of misfire, independently of the operation of said breechblock.

Still another object of my invention is to provide manually operated means for cocking a gun having a vertically slideable breechblock which is inexpensive to manufacture, simple to install on the gun, reliable in its function and safe to operate.

For a more complete understanding of the invention, reference may be had to the following description of an embodiment thereof, and to the drawing, of which

Fig. 1 is a fragmentary end elevational view of a breech mechanism, a portion being broken away to show in section.

Fig. 2 is a side elevation of the same, portions of the ring and block being broken away.

Fig. 3 is a view similar to that in Fig. 2, but showing the action of the automatic cocking device.

Fig. 4 is similar to Figure 3 except that it shows the action of the hand cocking device.

In the drawing a breech ring 10 of a gun is shown, within which a breechblock 12 is vertically slideable. The block carries a firing mechanism comprising a firing pin 14 housed in a firing pin guide 16, the guide being pressed by a suitable internal spring 49 in the usual manner. The firing mechanism is removably held in place in the block by a retainer 18 secured in the block by a bayonet joint connection. The firing pin and its guide are held in cocked position by a sear 20 which engages a bottom lug 22 on the guide 16 and riding in slot 15. To release the firing pin, the sear 20 is pushed inward against its spring 21 by a plunger 24 which extends through the wall of the ring 10 and is pressed by any suitable trigger mechanism (not shown).

For automatically cocking the firing pin and guide, a cocking lever 30 is rockably mounted on the breechblock 12. As indicated in Figs. 1 and 2, the cocking lever comprises an upwardly projecting arm 32 having a nose 34, a downwardly extending arm 36 having a lateral extension 37 at its lower extremity, and an intermediate shaft portion 38 which is cylindrical and fits into a corresponding recess in the block. The extension 37 of the lower arm 36 projects through an aperture 39 in the block to engage a lateral lug 40 on the firing pin guide so as to move the guide and pin to cocked position when the cocking lever 30 is rocked in a clockwise direction as shown in Fig. 2. Such rocking movement is brought about, when the breechblock 12 descends from its elevated breech-

closing position toward its breech-opening position, by the engagement of the nose 34 on a cam member 42 which is mounted on the breech ring 10, this action being illustrated in Fig. 3. As the block descends further to open the breech fully, the nose rides off the cam 42 and engages an inner face 43 of the ring 10, and the rear relieves the cocking lever of the pressure of the firing pin spring. As the block 12 thereafter rises to its breech closing position, an inclined end surface 44 on the upper arm 32 engages the cam member 42 and rocks the cocking lever until the nose 34 rides on the cam member. This rocking movement is against the pressure of a spring-pressed plunger 45 which tends to hold the nose 34 in engagement with the cam member 42 or the surface 43, by pressure on shoulder 50.

It is sometimes desirable to cock the pin without opening the breech, as for example, after a misfire. To this end, the cam member 42 is mounted on a shaft 46 which is journaled in a wall of the breech ring 10 and projects beyond the outer face thereof, as indicated in Fig. 1, to support a handle 48 mounted thereon. When the block is in its elevated position, as shown in Fig. 4, operation of the handle 48 rocks the cam 42 against the upper arm 32 of the cocking lever 30. This cocks the guide and pin as hereinbefore described.

I claim:

1. In a gun, a breech ring, a breechblock translatable mounted in said breech ring for movement from a first closed position to a second open position, a firing pin slidably mounted in said breechblock, spring means urging said firing pin into firing position, a cam member pivoted in said breech ring adjacent said breechblock, manually operable means externally mounted on said breech ring and directly connected with said cam member to pivot the same, a cocking lever pivoted in said breechblock and having a first portion engaging said firing pin to retract the same against the action of said spring means, said cocking lever also having a cam portion engaging said cam member, said cam portion engaging the cam member, without movement of the cam member, to pivot said cocking lever and cock said firing pin

5 automatically in response to translation of said breechblock to open position, said manually operable means being operable to pivot said cam member and, by engagement of said cam member with said cam portion, to pivot said cocking lever and thereby cock said firing pin while said breechblock is in closed position.

2. In a gun, a breech ring, a breechblock slideable in said breech ring transversely of the bore axis of said gun, a firing pin slidably mounted in said breech ring from a first cocked position to a second firing position, a double-armed cocking lever fulcrumed in said breechblock and pivotable to cause one arm to engage and retract said firing pin from second to first position, and means for pivoting said lever in response to sliding of said breechblock to open position, said means comprising a shaft journaled in one side wall of said ring, a cam member fixed to one end of said shaft for engagement with the other arm of said cocking lever as the breechblock slides to open position, a manually operable handle fixed to the other end of said shaft exteriorly of said breechblock, said cocking lever being pivoted to cock said firing pin either by sliding movement of said other arm over and in contact with said cam member as said breechblock is opened, or by pivotal movement of said cam member in response to turning of said handle while said breechblock is closed.

WILLIAM SUMMERBELL.
